PATENTED
JUN 25 1867

Fig. 1.

Fig. 3.

Fig. 2.

United States Patent Office.

DAVID HATHAWAY, OF TROY, NEW YORK, ASSIGNOR TO FULLER,
WARREN & CO., OF THE SAME PLACE.

Design No. 2,686, dated June 25, 1867.

DESIGN FOR THE PLATES OF A STOVE.

The Schedule referred to in these Letters Patent and making part of the same.

TO ALL WHOM IT MAY CONCERN:

Be it known that I, DAVID HATHAWAY, of the city of Troy, in the county of Rensselaer, and State of New York, have invented or produced a new and original Design for Plates of a Stove, of which the following is a sufficient description, reference being had to the accompanying photographs, in which—

Figure 1 is a view of the upper part,

Figure 2 of the lower part, and

Figure 3 of the whole of a stove in which my said design is embodied—

Like parts being marked by the same letters in the different figures.

In this invention or production the design of each side plate A of the base of the stove consists of the peculiarly grooved panel *a*, shaped and arranged as shown in figs. 2 and 3. The design of each plate B of the lower portion of the main cylinder of the stove consists of four pilasters, *b*, supporting the frame *c* of three panels *d*, with spires *e* and pendants *f*, all shaped as represented in figs. 3 and 2. The design of each plate C of the upper portion of the main cylinder of the stove consists of the four pilasters *g*, supporting three arches *h*, with pendants *i*, all shaped and arranged as shown in figs. 1 and 3, some parts being covered or obstructed by the door *z* in front and the smoke-pipe collar *y* in rear. The design of the main top plate D consists of four raised laterally projecting circular caps or cups *k*, shaped and ornamented by border mouldings, and arranged in combination with the ornamented intervening parts *j*, as represented by figs. 3 and 1; and the design of the cap-plate E consists of the border moulding *l* and swelling surface *m*, shaped and ornamented along its inner and outer edges *n* and *o* as shown by fig. 1.

What I claim as my invention or production, and desire to secure by Letters Patent, is—

The design of the plates A, B, C, D, and E of a stove, as herein specified and shown by the accompanying photographs.

In testimony whereof I hereunto set my hand this twenty-second day of May, 1867.

DAVID HATHAWAY.
